UNITED STATES PATENT OFFICE.

JOHN JACOBSON, OF ROCKFORD, ILLINOIS.

CAR-REPLACER.

1,346,962.

Specification of Letters Patent.

Patented July 20, 1920.

Application filed October 7, 1919. Serial No. 329,035.

To all whom it may concern:

Be it known that I, JOHN JACOBSON, a citizen of the United States, residing at Rockford, in the county of Winnebago and 5 State of Illinois, have invented certain new and useful Improvements in Car-Replacers, of which the following is a specification.

This invention pertains in general to railways, and has more particular reference 10 to car replacers of the rigid block type.

The primary object of the present invention is to provide a car replacer of generally improved construction, including two block elements, one adapted only for use outside 15 of the rails and the other inside thereof. My invention contemplates the building of these blocks in such novel manner that they will serve positively and effectually to 20 guide a derailed truck into the proper position on the rails.

Another object of my invention is to provide replacer blocks adapted to be associated with the rails in a novel manner and including side flanges which constitute guides 25 coöperating with shiftable guide bars on the blocks for guiding the wheels into position above the rails.

Still another object resides in the provision of a replacer block having a detachable rail clamp or flange which may be easily replaced by a new one in the event 30 that it is broken under the severe side thrust often imposed while replacing a car.

My invention further contemplates the 35 provision of novel means for supporting the blocks at different elevations in accordance with variations in the height of rails.

Other objects and attendant advantages 40 will be appreciated as the invention becomes better understood by reference to the following description when considered in connection with the accompanying drawing, in which—

Figure 1 is a plan view illustrating dia- 45 grammatically an arrangement of my improved car replacer blocks in working position;

Figs. 2 and 3, plan views of the outside and inside blocks, respectively, with the 50 rail clamps detached;

Figs. 4 and 5, side views of the parts shown in Figs. 2 and 3;

Figs. 6 and 7, vertical longitudinal sec- 55 tional views through the parts shown in Figs. 2 and 3 respectively;

Figs. 8 and 9, front views of the outside and inside replacer blocks respectively; and

Figs. 10 and 11, cross-sectional views taken on the lines 10—10 and 11—11 of Figs. 4 and 5, respectively.

60

As mentioned above, my invention contemplates the provision of a pair of car replacer blocks, one adapted only for use at the outside of the rails and the other inside thereof. This is for the purpose of 65 constructing each block to suit the peculiar conditions and requirements incidental to replacing or rerailing a car or locomotive truck, as will be presently seen. Referring to the drawing, it will be observed that the 70 outside replacer block is designated generally by the character 14 and inside block by 15. Each block is cast integral to the requisite shape except for the rail clamping or bracing means, which I prefer to 75 make as a separate detachable element. Considering first the construction of the outside block, it will be observed viewing Fig. 6, that this block is shaped to provide an inclined top surface 16, the high end 80 of which is supported at the proper elevation by means of a detachable shim 17. The outer vertical sides 18 of this block are substantially straight longitudinally thereof and converge toward the high end. 85 Above each side 18 the body of the block is extended outwardly providing a ledge 19 adapted to overlie and rest upon the top of a rail. The side edges of this block are further shaped to provide upstanding 90 flanges 21 extending substantially coextensive with the length of the block, the high end of each flange extending over and beyond the inner side of the rail with which the respective flange coöperates as shown 95 in Fig. 1. The block is held in coöperative relation with the rail by means of a rail-engaging flange or element designated by character 22. This element 22, detachably secured to the block 16 by suitable means 100 such as a bolt 23, is shaped to provide at each side of said block and in longitudinal alinement with the sides 18 and ledges 19, a rail-engaging flange 24 adapted to fit over the head of a rail and hold the block in 105 juxtaposition thereto. In this instance, the supporting shim 17 rests on the base of the rail and supports the block medially at its high end. A shiftable guide bar 25 pivotally mounted intermediate its ends at 110 26 on top of the block and shaped to conform to the inclined surface thereof is adapted to be secured in any of a plurality of positions in which its forward end 27 is

disposed in such proximity to either flange 21 as to properly guide the wheel flange onto the rail. The guide bar 25 also serves as a tread bar upon which the tread of the 5 wheel is adapted to roll as it moves along the replacer block. As shown in Fig. 1, the wheel 28 of the truck being replaced will be guided by and between the bar 25 and the flange 19 to a position directly 10 over the rail 29 so that said wheel will positively roll onto the rail with the wheel flange inside thereof. It is preferred that the rail-engaging element 22 shall be of cast steel, while the block 14 will be cast of 15 iron. In the event that the element 22 is broken from excessive strain, this part may be easily replaced by a new one. Supporting shims 17 of different height are supplied so that the replacer block may be 20 supported at the proper height regardless of variations in rail sizes.

The inside replacer block is very similar in construction to the outside block except that each upstanding flange 31 is of greater 25 width than the corresponding flange 21 of the outside block and is shaped to provide a flat upper surface upon which the tread of the car wheel is adapted to roll. Each flange 31 is shaped to extend entirely over 30 the respective rail with which it is associated, as shown plainly in Fig. 1, so that such flange serves not only as an outer guide for the car wheel, but also as the supporting surface upon which the tread of the wheel 35 rolls while being returned to the proper position over the car rail. The inner block is equipped with a removable rail-attaching element 32 similar in construction to the element 22 above described. As shown plainly 40 in Fig. 9, the part 32 conforms on its upper surface to the shape of the ledges 31 and is equipped with depending rail-engaging flanges 33. A shiftable guide bar 34 similar to the bar 25 mentioned above, is adapted 45 to be locked with its upper or forward end in operative relation with either flange 31, by means of a pin or bolt 35. It will be noted that the upper or forward end of the bar 34, together with the adjacent flange 31, 50 form converging guides which will lead the flange of the wheel 36 into proper position at the inner side of the rail. By constructing the blocks in the manner described they may be quickly attached to the rails 55 and firmly held in operative relation thereto. It will be further noted that the up- 60 standing guides at the side of each block and the shiftable guide bars form converging guides which positively lead the flanges of both car wheels to the inside of the rails so that the wheels will drop into proper position thereon. It is preferred that the blocks each be cast to the desired shape and reinforced by suitable longitudinally extend-

ing ribs as indicated in cross section in Figs. 65 10 and 11.

It is believed that the foregoing conveys a clear understanding of the principles and objects of my invention, and while I have illustrated and described but a single working embodiment thereof it should be understood that various changes might be made in the construction and arrangement without departing from the spirit and scope of the invention as expressed in the appended 75 70 75 claims, in which:

I claim:

1. A car replacer comprising a block having an inclined top, means for holding said block in juxtaposition to a rail, and a removable block for supporting the high end 80 of the inclined block, whereby to be substituted by a supporting block of different size to properly accommodate the inclined block to the size and shape of the rail. 85

2. A car replacer adapted for use only at the outside of either rail, comprising a base having an inclined top wider at its low end than at its high end and having an upstanding flange at each side extending substantially co-extensive of the length of the block, the block so shaped that its inclined surface extends over and to the inner side of each rail when in operative relation thereto, and each flange extending over and beyond the 90 inner side of each rail when associated therewith. 95

3. A car replacer comprising a block having an inclined top, means at each side of the block for holding it in juxtaposition to a rail, an upstanding flange at each side of the block for guiding a wheel longitudinally thereof into coöperative relation with the rail, and a guide bar pivoted intermediate 100 its ends on top of the block and adjustable about its pivot to position its forward end in such proximity to the adjoining flange as to guide the wheel flange into the proper position above the rail. 105

4. A car replacer comprising a pair of blocks, one for the outside of either rail and the other for the inside thereof, each block having an inclined top and outer rail-engaging sides converging toward the high end and also having an outstanding ledge extending over the top of the rail at said high end, an upstanding guiding flange along each side of each block, the latter flanges of both blocks terminating at their high ends substantially in alinement with the inner edges of the respective rail head with which each block is associated, and a shiftable guide bar on each block adapted to define with either guiding flange thereof a converging guideway for guiding the flange of the 110 car wheel into proper position over the rail 115 120 125

JOHN JACOBSON,
